UNITED STATES PATENT OFFICE

WILLIAM MORE DECKER, OF BUFFALO, NEW YORK

NURSING BOTTLE

Application filed March 3, 1927. Serial No. 172,475.

This invention relates more particularly to the type of sanitary nursing bottles comprising a neckless, wide-mouthed food-cell or receptacle and a so-called breast-nipple having a correspondingly large base stretched over an annular bead at the top of the cell.

In applying a breast-nipple to such a cell or receptacle, the breast is liable to be drawn down farther over one side than the other, 10 distorting it more or less and impairing or destroying its desired mobility. Such over-stretching, moreover, weakens it in time, causing it to lose its grip on the cell, as well as shortening the life of the breast-nipple.

One object of the invention is to provide 15 the food-receptacle with simple stop means for predetermining the proper and uniform application-limit of the breast-nipple to the receptacle, thus guarding against the objections resulting from its distorted or improper application.

A further object is to so contrive the stop device that it serves also as a guard for baffling attempts of the nursing infant to get 20 its fingers under the base of the breast and pull it off the food-receptacle.

In the accompanying drawings:—Figure 1 is a side elevation of a nursing bottle embodying the invention. Figure 2 is a vertical section of the upper portion of the same. Figure 3 is a side elevation of the food-cell or receptacle. Figure 4 is a cross-section on line 4—4, Fig. 3.

Similar characters of reference indicate 35 corresponding parts throughout the several views.

The neckless, wide-mouthed food-cell 10 may have the conventional cylindrical form shown in the drawing. At its upper end it is 40 provided with the customary annular locking rib or bead 11 under which engages the usual locking rib or flange 12 at the base of the breast-nipple 13.

Arranged below this locking rib and part 45 allel therewith is a second annular stop-rib or bead 14 which predetermines the extent to which the breast of the nipple can be stretched over the locking head 11 of the receptacle to apply or adjust it properly and uniformly 50 thereon around the entire circumference of

the breast. This stop-bead is spaced such a distance from the locking bead that the lower edge of the breast abuts against the upper side of the stop-bead when the breast is stretched over the locking head far enough to 55 securely interlock therewith. In the preferred embodiment of the invention, the space or groove 15 between the two beads is just wide enough to receive the base-flange of the breast, as shown in Fig. 2, and the upper face of the stop bead is flat to form an abrupt seating shoulder for the breast-nipple, as shown in the drawings, but the form or cross section of the stop-bead may be modified within the scope of the appended claims, 60 if desired. By this stop-provision, unequal stretching and distortion of the breast-nipple is obviated and its desired mobility and flexibility is preserved.

This improved cell is also especially desirable in connection with the breast-nipple shown and described in Letters Patent of the United States No. 1,207,377, issued to me December 5th, 1916. The dome-shaped breast of that nipple has an external annular rim 65 midway of its height to prevent its collapse. When this wide-rim breast begins to collapse, its lower portion folds inward and downward and reduces the internal diameter of the mouth of the food cell, arresting the further 70 descent of the mid-rib at the constricted cell-mouth and preventing complete collapse of the breast-nipple. This infolding of the breast cannot take place when it is drawn 75 down over the cell farther on one side than the other, but by providing the cell with the stop or limitation bead 14, such over-distension is prevented and the breast and its anti-collapsing mid-rib are permitted to function 80 properly.

The stop-bead performs the additional function of a guard or baffle under the lower edge of the applied breast which prevents the babe from dislodging or removing it.

This improvement not only insures the uniform application or adjustment of the breast-nipple to the food-receptacle and prevents 95 too easy removal of the same from the receptacle by a nursing infant, but by preventing over-stretching and weakening of the breast 100

preserves its necessary strong grip on the receptacle for a long period, thus lengthening its life.

I claim as my invention:—

- 8 1. In a nursing bottle, the combination with a neckless, wide-mouthed food-receptacle having an annular bead at its upper end and a breast-nipple therefor having an annular internal locking rib at its base engageable under said receptacle-bead, of a second annular bead formed on the receptacle below and in spaced relation to said first-named bead to be engaged by the lower edge of said locking rib and constituting a guard for limiting and restricting the placing of the breast-nipple over the food-receptacle, both of said beads projecting beyond the face of the receptacle.
- 10 2. In a nursing bottle, the combination of a breast-nipple having a locking rib at its base, and a neckless wide-mouthed food-receptacle having a pair of annular beads both projecting beyond the surface of the receptacle and spaced apart to form an intervening annular groove whose bottom is substantially in line with the receptacle-surface and which is approximately as wide as the locking rib of the breast-nipple, the lower bead constituting a stop to predetermine the application-
- 15 3. limit of the breast nipple and the upper bead constituting a locking element over the side and top of which the lower portion of said nipple is adapted to snugly bear in a stretched condition.
